UNITED STATES PATENT OFFICE.

JOSEPH WEBB, OF BEAVER, PENNSYLVANIA.

DESIGN FOR A LAMP GLOBE OR SHADE.

SPECIFICATION forming part of Design No. 16,420, dated December 15, 1885.

Application filed November 4, 1885. Serial No. 181,865. Term of patent 7 years.

To all whom it may concern:

Be it known that I, JOSEPH WEBB, a citizen of England, residing at Beaver, in the county of Beaver and State of Pennsylvania, have invented certain new and useful Improvements in Designs for Glass Lamp Globes or Shades; and I do hereby declare the following to be a full, clear, and exact description of the invention, reference being had to the accompanying drawing, which forms part of this specification.

This invention has relation to designs for lamp globes or shades or similar articles; and it consists in the surface ornamentation and configuration hereinafter described, and shown in the accompanying drawing.

The globe or shade is of the ordinary contour or outline, and one of the features of my invention consists in the fluting on the upper edge, as shown at *a*.

The body of the shade or globe is ornamented with diagonal pillars *b b*, having rounded or oval faces, and bevels *b' b'* at their upper and lower ends. Between the pillars *b b* the surface of the globe or shade is occupied by diamond-shaped or pyramidal pro-

jections or points *c c c*, forming the well-known "hob-nail" pattern, such points or projections being the product of angular or V-shaped grooves running horizontally and perpendicularly. At the base and above the neck horizontal ridges *d d d* are formed.

Having described my design, I claim—

1. The design for globes or shades, consisting of the substantially hemispherical body having parallel rounded pillars extending diagonally over the hemispherical portion and the intervening pyramidal projections, substantially as shown and described.
2. The design for lamp globes or shades, consisting of the diagonal rounded pillars *b b*, the intervening diamond or pyramidal projections, and the fluting *a a*, substantially as described and shown.

In testimony that I claim the foregoing I have hereunto set my hand this 2d day of November, 1885.

JOSEPH WEBB.
